F. J. Hartman.

Patented July 24, 1928.

UNITED STATES PATENT OFFICE.

WILLIAM U. GRIFFITHS, OF PHILADELPHIA, PENNSYLVANIA.

DRAIN BOARD.

Application filed March 3, 1924. Serial No. 696,719.

My invention relates to drain-boards which are adapted to be employed in connection with sinks and on which dishes, kitchen utensils and the like are adapted to be placed after having been washed. The water which drains from the said dishes is caught by the drain-board and runs therefrom into a kitchen sink or the like.

Drain-boards have heretofore, as far as I am aware, been constructed by casting the same to the particular dimensions and shapes desired. They have been necessarily heavy and the cost of the metal entering into their construction has been unnecessarily large.

The general object of the present invention is to provide a drain-board of relatively thin sheet metal pressed by suitable dies or by other means into the shapes desired.

A further object of the invention is to provide a drain-board of the character indicated in combination with means whereby it may be satisfactorily supported in proper relation to an edge or end portion of the usual kitchen sink.

To these and other ends my invention comprehends the construction and arrangement of parts as hereinafter fully described in the specification, particularly pointed out in the claims and as disclosed in the drawings in which I have illustrated convenient forms of mechanical embodiment thereof. However, it will be understood that changes in the details of construction may be made within the scope of the claims without departing from the invention.

In the drawings:

Fig. 1 is a view in side elevation of a drain board structure embodying the invention, a portion of the edge thereof being broken away to show more clearly a detail of the structure, and a portion of a sink upon which one end portion of the board rests being shown in section;

Fig. 2 is a vertical sectional view taken on the line 2—2 of Fig. 1;

Fig. 3 is a transverse vertical section taken on the line 3—3 of Fig. 1; and

Fig. 4 is a view in perspective of a bar by means of which the bracket shown in Figs. 1 and 2 is secured to the drain board.

Referring to the drawings: 1 designates a kitchen sink of any known construction, and 2 designates a drain-board formed of pressed sheet metal. In the pressing of the same flanged portions 3 are formed which

project downwardly from the opposite sides and the outer end portion thereof. The opposite side edges of the board are curved and taper inwardly as indicated at 4 and terminate in an inwardly and downwardly extending tongue-like portion 5. The under side of the board adjacent the margin thereof is pressed upwardly so as to form a marginal upwardly extending ridge 6 which operates to prevent the water which may drain from dishes which have been washed and placed upon the board from running over the sides and outer end thereof and dripping onto the floor. These marginal ridges 6 terminate at the inner end of the board upon opposite sides of the inwardly and downwardly extending tongue-like portion 5.

It will be apparent that what I have termed the inner tongue-like end portion of the board is supported upon the upper edge of one end of the sink 1.

The lower edges of the downwardly extending flanges 3 at the opposite sides and outer end of the drain-board are provided with horizontally and inwardly extending flanges 45. A bar 46 is secured at its opposite ends to the upper sides of the horizontal flanges 45 which extend inwardly from the flanges 3 at the opposite sides of the drain-board. The bar 46 is secured to the said horizontal flanges 45 by means of screw threaded bolts 47 having nuts 48 upon the screw threaded ends thereof, as shown. The upper side of the bracket 50, which is of usual construction, is secured to the under side of the bar 46 by means of bolts 51 and nuts 52 secured to the screw threaded ends of said bolts. The other side or leg of the said bracket is secured to the adjacent vertical side of a wall by means of screws 53.

It is desirable that the bracket 50 shall occupy a position in a vertical plane as shown in Fig. 1 of the drawings.

As usual the drain-board is inclined toward the sink 1. Such inclination is apparent from Fig. 1 of the drawing. In order, therefore, that the bracket which is secured to the under side of the bar 46 shall occupy a vertical position as shown it is necessary that the portion of the under side of the said bar with which the side of the bracket contacts shall be slightly inclined, as is clearly shown at 54 in Fig. 4. The inclination is somewhat exaggerated but it should be sufficient to compensate for the inclination of the drain-board toward the sink 1. The under

side of the opposite end portions of the bar 46 adjacent its opposite ends is cut away as indicated at 55 so as to form flat portions parallel with the opposite side of the bar 46 which rest upon the upper side of the inwardly extending side flanges of the drain-board.

For the purpose of preventing tilting of the drain-board, in case a weight should 10 be placed upon the outer end portion thereof to the right of the bracket 50, as shown in Fig. 1, I have provided a holding member comprising a shank portion 57 which is secured to the wall adjacent to which the drain-board is located by means of screws 58. The upper end of the said holding member is provided with a hook-like portion 59 which engages the inwardly extending flange 45 situated adjacent the said wall. 15 It is apparent that by reason of the engagement of the hook portion 59 of the holding member with the flange 45 which projects forwardly from the wall the drain-board is held firmly in fixed relation to the sink 20 1 and cannot either be tilted by a force exerted downwardly upon the outer end portion thereof or by a force exerted upwardly upon the inner portion thereof; also the presence of the holding member comprising the hook portion 59 prevents the drain-board 25 30 from being pulled outwardly away from the wall adjacent to which it is situated.

Having thus described my invention, what I claim and desire to secure by Letters Patent is:

1. In a drain-board structure, in combination, a drain-board having depending flanges at its opposite side edges from the lower edges of which inwardly extending flanges project, a cross bar secured to the inwardly extending flanges at points approximately midway of the opposite ends thereof, a bracket secured to said cross bar and to a support, and means for preventing tilting movement of the said drain-board with respect to the said bracket.

2. In a drain-board structure, in combination, a drain-board having depending and inwardly extending flanges at its opposite side edges, a cross bar secured to the inwardly extending portions of said flanges, a bracket having one leg secured to the said cross bar, and means for securing its other leg to the adjacent portion of a vertical sup-

port, the said bracket and bar having connection with the said drain-board at points intermediate its outer and inner ends, a holding means having connection with the said support and being in engagement with the inwardly extending flange adjacent said support at a point between the said bracket and the inner end of the said drain-board.

3. In a drain-board structure, in combination, a drain-board having downwardly extending flanges at its opposite side edges, 65 from the lower edges of which project inwardly extending flanges, a cross bar supported upon the inwardly and horizontally extending flanges, the intermediate portion of said cross bar being tapered transversely 70 of its length toward a sink into which water is adapted to drain from the said drain-board, a bracket the upper side of which is secured to the under side of said bar and the vertical side of which is secured to an adjacent vertical wall, and a holding means connected with said wall and being in engagement with one of the said inwardly and horizontally extending flanges, substantially 75 as and for the purpose described.

4. In a drain-board structure, the combination of a drain-board having downwardly extending flanges at its opposite side edges, a supporting bracket having a horizontal portion which extends underneath and 85 transversely of the length of the said drain-board, a bar mounted upon the said horizontally extending portion, the drain-board resting upon said bar, and the opposite ends of said bar having connection with the said 90 side flanges.

5. In a drain-board structure, the combination of a drain-board having downwardly extending flanges at its opposite side edges, the lower edges of which flanges are 95 provided with inwardly extending flanges, a supporting bracket having a horizontal arm which is located underneath and extends transversely of the length of the said drain-board, a bar mounted upon the said horizontal arm and having its opposite ends in engagement with the said flanges whereby the 100 said drain-board is secured to the said bar.

In testimony that I claim the foregoing as my invention I have hereunto signed my 105 name this 29th day of February, A. D. 1924.

WILLIAM U. GRIFFITHS.
